UNITED STATES PATENT OFFICE.

THOMAS J. NEWBERRY AND JOHN V. ERICSON, OF CHICAGO, ILLINOIS.

RAILROAD FREIGHT-CAR.

SPECIFICATION forming part of Letters Patent No. 653,359, dated July 10, 1900.

Application filed January 8, 1900. Serial No. 712. (No model.)

To all whom it may concern:

Be it known that we, THOMAS J. NEWBERRY and JOHN V. ERICSON, citizens of the United States, residing at Chicago, in the county of Cook and State of Illinois, have invented certain new and useful Improvements in Railroad Freight-Cars, which are fully set forth in the following specification, reference being had to the accompanying drawings, forming

10 a part hereof, and in which—

Figure 1 shows our said improved railroad-car in two halves, which are joined on the central-section line 2 2, whereof the first or left-hand half is shown in exterior view, while 15 the second or right-hand half is shown as an interior view, the same being a transverse section through its greater depth, so as to fully show both the lower and upper parts. Fig. 2 is in part a longitudinal section on the plane 20 2 2 of Fig. 1 and in part an exterior elevation with fragments of the walls broken out to show the parts beyond. Fig. 3 shows a top view of the lower parts *a*, from which one tank *j* is removed and whereof the other tank is 25 shown in part interiorly. Fig. 4 shows a corner of our car rigged as a flat-car. A portion of the tanks are shown, and the floor is raised to show said tanks. A part of the wood of the floor is also removed. Fig. 5 shows an 30 end view of the floor shown in perspective in Fig. 4, on an enlarged scale from that of the preceding figure, and is on a plane cutting through the axes of the bolts to show how the planks are held to the metal floor, and it also 35 shows how the stakes and stake-pockets are made. Fig. 6 shows a transverse section of our car at the truck or near the king-bolt.

Like letters of reference denote like parts of the drawings.

40 The object of our invention is to provide a freight-car construction wherein the efficiency of the device shall be increased over prior constructions and shall exceed the same in durability, be entirely or almost entirely 45 built of steel, and be fireproof, and also be adapted for carrying liquids in bulk and solids at the same time—as, for instance, oil in the tanks and grain in the car-body. To attain said desirable ends, we construct our 50 said car in substantially the following manner, namely:

On the ordinary trucks *z* we set vertical

sheet-steel webs *c c' c²*, which are cut out or notched on the inclined lines *t* and horizontal lines *t'* at their ends to make room for the 55 trucks, as shown, and connect said ends with a horizontal solid web of sheet-steel *d*, which lies on a bolster *e*, crossed by longitudinal pieces *i²*, forming the sides of the draw-bar space *i*, which at their rear ends are secured 60 to the central web *c* when said number of webs are used, as fewer or more such webs may also be used. The outer members of 65 said webs are spread apart as far as the width of the car-body *b* and are stayed at suitable distances with U-shaped channel-irons *f*, whereof the lower ends are connected by a cross-channel *f²*, both parts of which are filled with 70 cushions *f'*, preferably of wood of suitable quality, and at the corners of said channel-irons are attached suitable braces *g* to said channels and to said webs. Said webs are also provided with flanges *f³* at their lower edges and at their upper edges with like flanges *f⁴* for the purpose of giving lateral rigidity to said 75 webs. Stake-pockets *h* are secured to the upper edges of the outer webs to complete their construction and to which is added the bumper-bar *h'* at the ends and a king-bolt *i'* for connection with the trucks. Into said skeleton 80 frame are mounted one or more sheet-steel tanks *j*, rectangular in transverse section, which are at their tops flush with the tops of said webs, and thereby form a support for a separate car-floor *A*, suitable for carrying 85 lumber and all kinds of goods which can be transported on an open flat-car, and at the same time the tanks may be filled with oil or other liquids. Said floor *A* is formed of sheet metal *r^x*, provided with ribs *r⁴*, between 90 which are held boards *q'* by means of bolts *q²*, and to the edges of the sheet *r^x* are fastened short stakes *m²* to enter the stake-pockets *h* for holding said floor *A* to its place. The floor *r' r q*, Figs. 1 and 2, forms a fixed 95 part of the body *b*. Upon the lower part *a*, which consists of the vertical webs and their attachments, is placed the upper part of the car or car-body proper, *b*, constructed of sheet-metal sides and ends *m* and like-materied roof *n'*, with running-board *n*, all of sheet-steel. Flanges *f⁵*, integral with the under part of the walls *m*, fit on the flanges *f⁴* and are united by bolts *k*, while the sides *m* 100

are also stiffened by both vertical and diagonal braced channel-irons m' and m^2 of said U-shaped form. The roof is supported by sheet-metal rafters o , and the vertical channel-irons m' extend and enter into the stake-pockets h to securely connect the said parts a and b . The bottom or floor r' of the car-body part is also of sheet metal and fit for all ordinary use; but when desirable a floor of wood q is laid and held to place by the wooden side-lining or wainscoting p , and said steel floor may then be further strengthened by means of ribs r , extending up between each board to, or nearly to, the top of the floor. The tanks j are also provided with a suitable filler-opening l , shown on the interior of the car-body b ; but said filler may be placed at any suitable position, either inside or outside of the car-body. Angle-irons s are secured to the bottom of the metal floor r' on both sides of the central web c for the purpose of both stiffening the latter and for holding the several parts more securely to their place.

As the upper part of the car-body is removable, both it and each of the tanks j may be removed for the purpose of repair or use and, as shown, the lower parts used alone or as a flat in connection with oil or liquid transportation. The sheet-metal floor r' , with its ribs r and angle-iron stays s , may also be laid on the top of said tanks j without the body b above it, and the floor q held by means of nails or dowels r^2 , passed through holes in the ribs r . By means of this construction a floor of great strength and durability is obtained for a flat-car constructed as herein shown and described.

What we claim is—

1. The combination with end-notched, connected, cushioned, and braced sets of vertical webs, of tanks, with corresponding end notches, on said cushions, and flush with the top of said webs, substantially as specified. 40

2. The combination with vertical, transversely-connected and top-flanged webs, of a

removable, base-flanged, car-body and means to removably connect said flanges, substantially as specified.

3. The combination with end-notched, transversely-connected, vertical and flanged webs provided with means for giving transverse rigidity, of a car-body, flanged at the base of its walls, and means to connect said car-body and webs, substantially as specified. 50

4. The combination with a sheet-metal car-body and a sheet-metal floor, integral with its walls, of a wooden floor and wainscoting holding said floor, substantially as specified. 55

5. The combination with a sheet-metal car-body and a sheet-metal floor provided with ribs, and floor-boards between said ribs, of a wainscoting holding said floor to its place, substantially as specified. 60

6. The combination with flanged vertical webs provided with stake-pockets, of a sheet-metal car-body stiffened with channel-irons which extend into said pockets, substantially as specified. 65

7. The combination with flanged vertical webs provided with stake-pockets, of a sheet-metal car-body stiffened by channel-irons which extend into said pockets, and bolts through said flanges to connect said webs and car-body, substantially as specified. 70

8. The combination with end-notched vertical webs and trucks therefor, of a sheet-metal floor with ribs and boards between said ribs and pins through said ribs to hold said boards, substantially as specified. 75

9. In railroad freight-cars, the combination with vertical side webs, and a central web, having their top edges in the same plane, and transverse connections to said webs, of a floor and means to removably secure the same to said webs, substantially as specified. 80
